(57) **CLAIM**

The ornamental design for a baby sleepsuit with two zips, as shown and described.

DESCRIPTION

FIG. 1 is a front view of two zips associated with a baby sleep suit according to the design;

FIG. 2 is a rear view of the two zips associated with a baby sleep suit of FIG. 1;

FIG. 3 is a front view of the two zips associated with the lower portion of a baby sleep suit of FIG. 1;

FIG. 4 is a rear view of the two zips associated with the lower portion of a baby sleep suit of FIG. 1;

FIG. 5 is a front view of the two zips associated with a baby sleep suit of FIG. 1 shown with the zipper open and the two zips located on the right side;

FIG. 6 is a front view of the two zips associated with the lower portion of a baby sleep suit of FIG. 1 shown with the zipper open and the two zips located on the right side;

FIG. 7 is a front view of the two zips associated with a baby sleep suit of FIG. 1 shown with the zipper open and the two zips located on the left side; and,

FIG. 8 is a front view of the two zips associated with the lower portion of a baby sleep suit of FIG. 1 shown with the zipper open and the two zips located on the left side.

The broken lines are for the purpose of depicting portions of the baby sleepsuit with two zips and form no part of the claimed design.

1 Claim, 8 Drawing Sheets
